UNITED STATES PATENT OFFICE.

EDWARD L. SANDS, OF WEBB CITY, MISSOURI.

SAFETY-PIN.

SPECIFICATION forming part of Letters Patent No. 757,351, dated April 12, 1904.

Application filed February 10, 1903. Serial No. 142,726. (No model.)

To all whom it may concern:

Be it known that I, EDWARD L. SANDS, a citizen of the United States, and a resident of Webb City, in the county of Jasper and State of Missouri, have invented a new and Improved Safety-Pin, of which the following is a full, clear, and exact description.

This invention relates to improvements in safety-pins, the object being to provide a safety-pin formed of a single length of wire and so constructed that the pin member will be prevented from accidental displacement from its keeper or guard.

I will describe a safety-pin embodying my invention and then point out the novel features in the appended claim.

Reference is to be had to the accompanying drawings, forming a part of this specification, in which similar characters of reference indicate corresponding parts in all the figures.

Figure 1 is a plan view of a safety-pin embodying my invention. Fig. 2 is a section on the line 2 2 of Fig. 1, and Fig. 3 is a section on the line 3 3 of Fig. 1.

The safety-pin is formed of a single length of spring-metal wire, which is bent substantially midway of its length forming the back member 5, the turned end 6, and the pin member 7, which is pointed, so as to readily enter a fabric. The end 6 is provided at about its center with an inwardly-turned eye 8, and the opposite end of the back or body member is curved to form the double-loop members 9 10, which provide a guard or keeper for the pin-point. The end of the wire is coiled around the back, as at 11, and then it is flattened and extended across the loop, as at 12,

thus forming a flexible shield and guide for the pin passing into the loop. This flexible shield guides the pin into the loop or keeper from either side, so that it is convenient for either a left or right hand operator, and the pin always opens on the side it enters, which materially lessens the chances of the individual getting scratched.

As before stated, the improved pin is formed of a single length of spring-metal wire, an eye 8 being formed midway of the end 6, turned inwardly between the back and pin members, thereby forming a fulcrum from 50 which the pin receives the necessary spring, and the eye by being turned inward and practically within the plane of the back and pin members prevents any possibility of its entanglement with the fabric engaged by the pin. 55

Having thus described my invention, I claim as new and desire to secure by Letters Patent—

A safety-pin formed of a single length of wire bent substantially at its center forming back and pin members, an inwardly-extended 60 eye midway of the bend between the back and pin, a portion of the back member at the end opposite the eye being curved to form double loop members, and the end of the wire coiled around the back member and having a flattened portion extended between the loop members. 65

In testimony whereof I have signed my name to this specification in the presence of two subscribing witnesses.

EDWARD L. SANDS.
